SEDIMENT COLLECTING CAP

Application filed April 14, 1931. Serial No. 529,984.

Our present invention relates to the art of bottling accessories and more particularly to a sediment collecting cap which is intended for use on beverage bottles of the effervescent type.

5 The general purpose of our present invention is similar to that shown in our co-pending application, Serial No. 286,625, filed June 19, 1928. Many sediment collecting devices have been created but most of them have the

10 inherent fault of being difficult to clean. Others have small valve members, upon whose action little dependence can be placed. In our present case we believe we have overcome the outstanding disadvantages indicated and 15 at the same time are able to produce a bottle cap which clamps securely to the bottle, which can be made cheaply and be used over and over again without fear of any damage.

Therefore, 20 The principal object of our present invention is to provide a simple bottle cap which will collect and retain sediment precipitated by beverages.

25 A further object is to produce a sediment collecting cap that may be easily cleaned.

Other and more specific objects will be apparent from the following description taken in connection with the accompanying drawings, wherein

30 Figure 1 is an elevation partly in section, showing our sediment collecting cap secured to a beverage bottle.

Figure 2 is a fragmentary sectional view showing our bottle cap just as it has been removed from a bottle.

Figure 3 is a fragmentary view showing our valve arrangement in its seated position.

Figure 4 is a fragmentary sectional view through our bottle cap in the position in 40 which it is placed to catch sediment precipitated.

Figure 5 is a perspective view showing our valve member.

Figure 6 is a cross sectional view along the 45 line 6—6 of Figure 4.

Referring to the drawings, throughout which like reference characters indicate like parts, numeral 10 designates the body of our cap. This consists of a collecting chamber 12, an annular engagement groove 14 and

a coned portion 16 and may at times have a finish bead as 18. Cone portion 16 is provided, first, to make the attachment of the cap easier, and second, to more closely engage the beveled portion 20 of the average beverage bottle. We prefer to form body 10 of moulded rubber of such a temper that it can be distorted sufficiently to slip over and engage the cap bead 22 of beverage bottle. The exact 55 shape of chamber 12 is a matter of preference. It has been found desirable to have the general shape cylindrical, although for ease in manufacture it is usually more convenient to have it slightly coned with the small end at the closed end of chamber 12. This is a 60 manufacturing expediency and gives draft for the easy removal of cores which are used in the moulding operation.

The end wall 24 of chamber 12 should preferably be flat and normal to the axis of the 70 bottle when the cap is in place. This is desirable in order that the bottles may be easily stood upside down, it being necessary to so place the bottles in order that the sediment will filter downwardly and come to rest with- 75 in chamber 12.

Normally disposed, partially within the bottle B and partially within the cavity 12 is a valve member 30. This consists of a stem 32 upon which is mounted a valve 34. It is 80 believed apparent that valve 34 might be formed as a part of stem 32. However, owing to the variation in bottles it is often more desirable to have this valve formed so that it snugly encircles stem 32 and in this manner 85 may be readily adjusted.

As viewed in Figures 1 and 4 valve 34 should be up as high as will permit of a free flow of the sediment past it, or rather, between it and the bottle. This of course is 90 with the aim of providing the maximum available storage space in chamber 12 for the sediment. It has further been found desirable to form the lower end of stem 32 as a ball 36. This member might be dispensed 95 with.

However, referring to Figure 1, it is believed apparent that if no ball 36 were provided the stem 32 would lie in close contact with the inner surface of the bottle neck and 100

would thus form a natural lodging place for any sediment flowing downwardly. The ball shape of course could be easily changed to a conical shape with the point uppermost, as viewed in Figures 1 and 4.

Method of operation

In operating our device it is usual to fill bottle B with the desired fluid up to the usual level. Valve member 30 is then placed in position as indicated in Figure 3. The cap proper 10 is then grasped in the hand and the mouth of the bottle entered into the coned portion 16. By applying downward pressure and twisting the cap slightly, it will be found to go on very easily. It has been found, however, that it will engage more easily and smoothly if the caps 10 are soaked in water for a few minutes, or at least are thoroughly wet. The water in this case acts as an excellent lubricant, preventing any frictional engagement between the glass and the rubber cap.

The beverage bottle with the cap thus attached is then inverted as indicated in Figure 4. Valve member 30, due to its own weight, drops downwardly until the end of stem 32 engages the bottom wall 24 of the cap. This spaces the valve 34 at the proper distance both from the bottle itself and from the bottom of the cap. The bottle is allowed to stand in this manner until all the sediment has been precipitated. Ordinarily, little, if any, will lodge on the sloping surface 40 of the valve. In some instances, however, this may occur. This condition may be remedied, however, by inclining the bottle about as indicated in Figure 1 and slowly revolving it for a turn or two. This is normally sufficient to dislodge any sediment which may have come to rest on surface 40 or even on the upper surface of ball 36. The beverage should then be replaced to the position shown in Figure 4 until it is certain that all sediment has been precipitated. The bottle may then be inverted to the position indicated in Figure 3. The valve member 30 will drop downwardly until valve 34 engages the upper surface of the bottle mouth and seals the same. Now, normally the bottle will not be inverted until just before its content is to be used, but it is possible to invert the same at any time after the sediment has all been precipitated.

To open the bottle, body 10 is grasped by the hand and with a slightly twisting effort the cap is bent over to one side until it is entirely removed. This operation is normally best performed over some vessel, as it is very desirable to keep the bottle substantially upright and it usually entails, of course, the spilling of the contents of chamber 12. The valve member 30, however, has been found to adequately protect the open mouth of the bottle, even though it in some cases may be

removed from the bottle by being engaged by groove 14, as has been indicated in Figure 2.

The foregoing description and the accompanying drawings are believed to clearly disclose a preferred embodiment of our invention but it will be understood that this disclosure is merely illustrative and that such changes in the invention may be made as are fairly within the scope and spirit of the following claims:

1. A sediment collecting cap consisting of a body portion formed of resilient material and adapted to provide a sediment collecting chamber; an annular groove, disposed near the open end of said chamber, adapted to engage a bottle bead; a valve assembly having a coned valve adapted to engage the mouth of a bottle and a valve stem both disposed within said chamber and adapted to space said valve away from the end of said chamber.

2. A sediment collecting cap consisting of a body portion adapted to provide a sediment collecting chamber; means adapted to secure said chamber to a bottle neck; a valve assembly having a stem adapted to provide a guide for said valve assembly, and a valve disposed within said chamber and substantially midway upon said stem and having a coned face sloping toward the open end of said chamber adapted to seat on the outer mouth of a bottle.

3. A sediment collecting cap consisting of a body portion formed of resilient material forming a sediment collecting chamber; an annular groove, disposed near the open end of said chamber, adapted to engage a bottle bead; a valve assembly having a stem which is enlarged at one end, and a valve mounted upon said stem, said enlarged end adapted to rest on the inside of a bottle and said valve disposed within said chamber.

4. A sediment collecting cap consisting of a body portion formed of resilient material forming a sediment collecting chamber; an annular groove, disposed near the open end of said chamber, adapted to engage a bottle bead; a valve assembly, formed of resilient material, having a stem, and a valve disposed within said chamber so mounted upon said stem as to be spaced away from the end of the collecting chamber.

5. A sediment collecting cap consisting of a body portion forming a sediment collecting chamber; means adapted to secure said chamber to a bottle neck; a valve assembly having a valve adapted to engage the outer mouth of a bottle and a valve stem disposed within said chamber and adapted to space said valve away from the end of said chamber.

6. A sediment collecting cap consisting of a body portion, formed of resilient material and adapted to provide a sediment collecting chamber; an annular groove, disposed near

the open end of said chamber, adapted to engage a bottle bead; a valve assembly formed of resilient material, having a stem; an enlargement on one end of said stem adapted to engage the inside of a bottle; a valve slidably disposed upon said stem and having a coned face sloping toward said enlargement and positioned within said chamber and a portion of said stem, disposed within said chamber, extending beyond said valve.

In witness whereof, we hereunto subscribe our names this 7th day of April, A. D. 1931.
